UNITED STATES PATENT OFFICE.

ARMEN H. TASHJIAN, OF CLEVELAND, OHIO.

POLE OR POST.

Application filed December 31, 1925. Serial No. 78,582.

This invention relates to poles or posts for use particularly for supporting electric transmission lines, as street lighting poles, as trolley poles, as radio aerial masts, and the like.

The object of the invention is to provide an open steel pole, that is, a pole of skeleton steel construction, without recourse to riveting, welding or bolting in the assembling of its component parts, thus providing a pole of great rigidity and strength, particularly in the connection of its structural members, and of relatively low manufacturing cost.

The invention consists, essentially, in a pole or post, or the like, comprising a plurality of longitudinal members having channeled faces, lips flanking said channels, and a plurality of transverse members in the form of diaphragms or spiders arranged between the longitudinal members at spaced intervals throughout their length, and provided with arms for engagement with the channels of the longitudinal members, these arms being provided with knobs arranged for engagement with the lips of the longitudinal members, and these lips adapted to be clinched upon the arms and the knobs thereby imbedded in the lips, to form a rigid connection between the longitudinal members and the transverse members, as I will proceed now to explain and finally claim.

In the accompanying drawings illustrating the invention, in the several figures of which like parts are similarly designated, Figure 1 is an elevation showing a complete pole embodying my invention. Fig. 2 is an enlarged fragmentary detail of same. Fig. 3 is a section taken on the line 3—3 of Fig. 2. Fig. 4 is a plan view of a modified form of transverse member of spider by means of which six longitudinal members may be used in the construction of the pole or post as distinguished from the four longitudinal members illustrated in Figs. 1 to 3. Fig. 5 is a side elevation of the transverse member illustrated in Fig. 4. Fig. 6 is a plan view of a further modification of the transverse member. Fig. 7 is a side elevation of the form of transverse member illustrated in Fig. 6 and showing a longitudinal member connected therewith.

In the form of the invention illustrated in Figs. 1, 2 and 3, I have shown a pole or post having four longitudinal members 1, channeled as indicated at 2, these channels

being formed and flanked by lips 3. These longitudinal members are arranged around transverse members or spiders 4, spaced at suitable intervals throughout the length of the longitudinal members, and having arms 5 provided with knobs 6 adapted to be positioned within the channels of the longitudinal members and the lips 3 clinched upon them so that the knobs are imbedded in the material of the lips to form a rigid, non-slipping connection between the longitudinal members and the transverse members. By thus connecting the several longitudinal members by means of the transverse members or diaphragms or spiders, whereby no slippage or movement between the parts is permitted, I am enabled to produce an exceptionally sturdy and rigid pole construction.

As shown particularly in Fig. 1, the pole may be gradually tapered from top to bottom by providing appropriate bends 7 in the longitudinal members, the transverse members or spiders being made of diminishing size to accommodate the tapering of the pole.

In the form of the invention shown in Figs. 1, 2 and 3, wherein only four longitudinal members are used, I prefer to form the transverse members of two pieces of pre-formed stock, provided, during their fabrication, with the rows of knobs 6, as shown, and these pieces I bend into substantial U-shape, as shown in Fig. 1, to form the arms 5, and then I place one upon the other and weld the two together where they cross at 8.

In Fig. 3 I have shown a section through one of the arms 5 and the longitudinal member connected therewith illustrating the manner in which the knobs 6 are imbedded in the lips 3 when the latter are clinched upon the arms 5.

When it is desired to construct a pole or post requiring more longitudinal members than the pole of the type shown in Figs. 1 to 3, I may use for my transverse members or diaphragms the arrangement of parts shown in Figs. 4 and 5.

In this form of transverse member, I take a plurality of pieces 9 of the knobbed stock and bend them to angle form, as shown in Fig. 5, and then I weld the ends 10 of these angles to a plate 11 which may be either of circular form, as illustrated in full lines in Fig. 4, or of angular form, as illustrated in broken lines in Fig. 4. The appropriate

number of longitudinal members to correspond with the number of members 9 may then be assembled to form a post by clinching the lips of the longitudinal members upon the knobs 6 of the portions 12 of the angles 9.

In Figs. 6 and 7, I have illustrated a cast or forged transverse member or spider having spacers 13 carrying at their ends arms 14 provided with knobs 15. The longitudinal members are assembled upon spiders or diaphragms of this type in the same manner as hereinabove described by clinching the lips 3 upon the arms 14 and their knobs 15.

By constructing a pole or post in accordance with my invention, whereby welding, riveting and bolting are dispensed with in the connection of the longitudinal members with the transverse members, I am not only enabled to produce a pole or post at a lesser manufacturing cost than where welding, riveting and bolting are used, but the drilling of holes to receive rivets or bolts, and the weakening of the component members of the pole caused thereby is done away with. Moreover, the manufacture of poles in accordance with my invention is much simpler and speedier than by any other method with which I am familiar.

I have hereinabove described my invention as particularly adapted to the production of poles or posts for use as supports for electric transmission lines, as street lighting poles, as trolley poles, as radio aerial masts and the like, but it is to be understood that it is adapted also to the production of structural columns for building

construction, or of reinforcing elements for use in concrete construction.

Various changes are contemplated as within the spirit of the invention and the scope of the following claims.

What I claim is:—

1. A pole or post, or the like, comprising a plurality of channeled longitudinal members having lips flanking their channels, and transverse members having arms for cooperation with the longitudinal members, said arms adapted to be positioned within said channels and provided with knobs for engagement with said lips, and said lips adapted to be clinched upon said arms, said clinching imbedding said knobs in said lips to form a rigid connection between the longitudinal and transverse members.

2. In a pole or post, or the like, a plurality of longitudinal members, a plurality of transverse members arranged at suitable spaced intervals throughout the length of the longitudinal members, and means for connecting the longitudinal and transverse members comprising arms on the transverse members and lips on the longitudinal members, the arms of the transverse members being provided with knobs and the lips of the longitudinal members being clinched upon the knobs of said arms, the knobs being thereby immovably imbedded in said lips.

In testimony whereof I have hereunto set my hand this 29th day of December, A. D. 1925.

ARMEN H. TASHJIAN.
